UNITED STATES PATENT OFFICE.

WILLIAM JOSEPH STILL, OF LONDON, ENGLAND.

PISTON OF INTERNAL-COMBUSTION ENGINES.

1,323,115.

Specification of Letters Patent.

Patented Nov. 25, 1919.

Application filed May 19, 1919. Serial No. 298,203.

To all whom it may concern:

Be it known that I, WILLIAM JOSEPH STILL, of 7 Princes street, London, S. W. 1, England, engineer, have invented certain new and useful Improvements in Pistons of Internal-Combustion Engines, of which the following is a specification.

This invention relates to improvements in the pistons of internal combustion engines and has for its object to provide a piston which can be adequately cooled and which will at the same time stand the strains to which it is subjected in practice.

The pistons of such engines where the cylinders are of large bore necessarily involved large masses of metal and considerable difficulty is experienced in effectively cooling such pistons evenly throughout their mass. Pistons for internal combustion engines have been proposed with integral rings or annular ribs interposed between the piston crown and a supporting bolster on the piston rod so that oil or other cooling liquids can be introduced into the spaces formed between the ribs. In such cases, however, the only arrangement for permitting the circulation of the liquids has consisted in radial holes bored through the ribs so that the cooling fluid entering the central cylindrical chamber passes the next annular chamber radially through these radial holes and from this first annular chamber to the next annular chamber and so on in precisely the same manner. By this means the cooling liquid can find its way from the central chamber to the piston skirt and fill up the spaces of the piston.

In dealing with pistons of large area the heat absorbed by the pistons is, however, very great and in fact experience has shown that it amounts in some cases to as much as 40,000 British thermal units per hour per square foot of surface—which is equivalent to the production of 40 lbs. of steam per square foot of surface per hour. To dissipate this heat, particularly where steam is used as the cooling medium, it is necessary to provide a large area of radiation surface and cause the cooling fluid to flow rapidly in thin streams and in intimate contact over the whole of the radiation surface, and it is the object of my invention to provide a piston where these conditions can be fulfilled, and the invention consists broadly in providing a piston having ribs or projections formed between its crown and the

piston bolster in such a manner that adequate support will be afforded to the comparatively thin piston crown and the cooling fluid entering at the center of the piston will flow in thin streams through the passage in close contact with the radiation surface afforded by the ribs or projections to an annular space located at the piston crown. In the preferred construction of my invention the grooves or channels through which the cooling liquid flows intersect.

The invention is capable of considerable modification in matters of detail and in the accompanying drawings I have illustrated more or less diagrammatically and by way of example certain constructions and methods by which the invention may be carried out in practice.

In these drawings Figure 1 is a longitudinal section of a piston on line A—A of Fig. 2 constructed in accordance with my invention and particularly designed for use with steam as the cooling fluid although it will be appreciated that water or other cooling fluid can be provided for.

Fig. 2 is a partial plan or face view of the back of the piston with the supporting bolster removed.

Fig. 3 is a section on the line B—B of Fig. 2.

Fig. 4 is a partial face view of the bolster end of the piston rod showing in particular a convenient arrangement and disposition of the holes for accommodating the bolts which secure the piston to the piston rod.

Referring to these drawings and particularly to Figs. 1 to 4 the piston 1 provided with a skirt 2 and the usual packing ring 3 has its crown 4 provided with a system of grooving, the grooves 5 extending in depth from the inner face 6 of the piston crown to within a short distance of the outer face or wall 7 which, when the piston is in operation, is the combustion side of the piston. This grooving results in the production of a thin piston crown, and in order to give the piston as a whole the necessary strength, the piston proper is connected by means of the bolts 8 which pass through bolt holes 8^a to a bolster 9 on the end of the piston rod 10. The face 11 of this bolster abuts closely against the outer edges or surfaces of the ribs or projections 12 which are formed as a result of the grooving so that, in effect, the bolster supports the thin crown by its engagement with these ribs or projections 12.

The particular form of grooving illustrated particularly in Fig. 2 consists of series of adjoining circular passages, each series following an involute curve extending from a central recess 13 to the piston skirt 2, and if desirable an annular groove may be provided connecting the series of grooves at or near the outer periphery of the piston skirt. The circular grooves aforesaid can be cut 10 by means of trepanning tools, and the surfaces, which in practice are exposed to the cooling fluid, can be increased by screw threading the walls of the groove by means of a hollow tap, and similarly screw threading the circular projections 12 which are formed as a result of the trepanning operation.

The particular system of grooving hereinbefore described and as illustrated in Fig. 2 results in the provision of very large heat dissipating surfaces exposed to the cooling fluid and also results in the formation of the supporting ribs or projections 12. Upon reference to Fig. 2, of the drawings it will be seen that in this particular instance the supporting ribs or projections take two distinct forms one of which, designated 12^a may be described as a continuous involute rib having an irregular contour and the other 25 of which consists of a number of separate circular projections designated 12^b, following an involute curve. The piston hereinbefore described is particularly designed for that type of engine hereinbefore described in the 30 specification of my prior British Letters Patent No. 25356 of 1910 where steam is used expansively at the back of the piston and operates to cool it. It will be seen upon reference to Fig. 1 that steam entering from the 35 meet valve of the engine passes through the ports 15 in the cylinder cover 16—shown in dotted lines—and thence passes through the passages 17 to the center of the piston crown, and circulates through the grooves or 40 passages 5 to the periphery of the piston and at the end of the expansion stroke passes to exhaust as will be readily understood upon reference to the prior specification above 45 alluded to.

50 Pistons of the foregoing general character will be found capable of effective cooling by steam. Moreover such pistons will be very strong structurally by reason of the support

at the back afforded by means of the bolster to which the piston is connected as aforesaid 55 by means of a number of bolts which, where they pass through the piston crown may be of a section corresponding to the section of metal left between certain of the grooves whether that section be circular as in Fig. 2 60 or of other form.

While I herein show and describe one form of my invention, I would have it understood that changes may be made in the 65 form, proportion and construction of the several parts, without departing from the spirit of my invention, and within the scope of the appended claims.

In cases where steam is not used at the back of the piston or where cooling is desirable any suitable known means may be adopted for circulating the cooling fluid. For instance, the water or other cooling fluid may be passed in through the piston rod and out through a trombone or sliding joint 75 as will be readily understood.

What I claim and desire to secure by Letters Patent is:—

1. In an internal combustion engine, a piston rod having a bolster at its outer end, 80 said bolster having a centrally arranged recess in its outer side and passages leading to said recess, and a piston having its crown provided, on the inner side, with a central recess and with ribs and passages between 85 said ribs, said passages communicating with said recess; the said bolster of the piston rod abutting against and being secured to the crown of the piston.

2. In an internal combustion engine, a piston rod having a bolster at its outer end, 90 said bolster having a centrally arranged recess in its outer side and passages leading to said recess, and a piston having its crown provided on the inner side with a central 95 recess, and with ribs and passages between said ribs and communicating with said recess, the crown being further provided with an annular passage with which the first named passages communicate at their outer 100 ends; the said bolster of the piston rod abutting against and being secured to the crown of the piston.

In witness whereof I affix my signature.

WILLIAM JOSEPH STILL.
